S. S. WARD,
COMBINATION LOCK SWITCH.
APPLICATION FILED APR. 21, 1917.

Patented Mar. 26, 1918.

Inventor

SAMUEL S. WARD

By Watson E. Coleman
Attorney

UNITED STATES PATENT OFFICE.

SAMUEL S. WARD, OF VIENNA, SOUTH DAKOTA.

COMBINATION LOCK-SWITCH.

1,260,607.

Specification of Letters Patent. Patented Mar. 26, 1918.

Application filed April 21, 1917. Serial No. 163,613.

To all whom it may concern:

Be it known that I, SAMUEL S. WARD, a citizen of the United States, residing at Vienna, in the county of Clark and State of 5 South Dakota, have invented certain new and useful Improvements in Combination Lock-Switches, of which the following is a specification, reference being had to the accompanying drawings.

10 This invention relates to a combination lock switch and has for its primary object to provide a device of this character which is primarily designed for use upon automobiles for the purpose of preventing the operating circuits for the batteries and generator being closed by unauthorized persons.

15 It is also an important object of the invention to provide a very simply constructed switch of the above type, wherein the combination, the key to which is required in order that the circuit may be closed, can be easily changed.

20 It is a further general object of the invention to provide a combination lock switch which is highly serviceable and convenient in practical use and can be manufactured at relatively small cost.

25 With the above and other objects in view, 30 my invention consists in the novel features of construction, combination and arrangement of parts to be hereinafter more fully described, claimed and illustrated in the accompanying drawing, in which,

35 Figure 1 is a longitudinal section through a switch and casing or housing therefor, constructed in accordance with the preferred embodiment of my invention;

40 Fig. 2 is a section taken on the line 2—2 of Fig. 1;

Fig. 3 is a section taken on the line 3—3 of Fig. 1;

Fig. 4 is a detail perspective view of one of the circuit closing disks; and

45 Fig. 5 is a detail sectional view through one of the rotatable disks.

Referring in detail to the drawing, 5 designates a casing, preferably constructed of sheet metal, which may be of any suitable 50 form and size. Within this casing, the switch mechanism is arranged between the spaced end walls 6 and 7 respectively. To the end wall 6, upon the edge thereof, a sheet metal plate 8 is securely fixed, and is 55 provided upon its ends with the arms 9 disposed in diametrically opposed relation and

extending longitudinally within the casing 5. The terminals of these arms are suitably fixed to the other end wall 7.

The end wall 7 is provided with an opening in which a disk 10 is rotatably mounted, said disk being formed with a central opening. A sleeve 11 is rotatably mounted in said opening and is provided with a rectangular inner end portion 12 and with a 65 knurled head 13 on its outer end. A disk 14 of suitable insulating material is engaged upon the inner square end of said sleeve.

A second rotatable sleeve 15 is mounted within the sleeve 11 and projects beyond the 70 square end of the latter sleeve. A disk of insulating material 16 is engaged upon this projecting end of said sleeve. A third sleeve 17 is disposed through the sleeve 15 and is supported at one end upon the shank or bolt 75 18 fixed in the wall 6, and upon this latter sleeve a disk 19 of insulating material is engaged. The sleeves 15 and 17 are also each provided with a knurled head indicated at 20 and 21 respectively.

80 In the disk 14, a metal contact pin 22 is secured, the ends of the pin being flush with the opposite side faces of the disk. A similar pin 23 is also fixed in the disk 19. The intermediate disk 16 has an arcuate slot 23 85 therein, and a metal circuit closing plate 24 also of arcuate form is pivotally engaged intermediate of its ends upon a radially disposed pin 25 fixed in the disk. The terminals of the plate 24 are outwardly bent or 90 curved as indicated at 26, for sliding contact with the opposed faces of the respective disks 14 and 19. A wire spring 27 bears against one end of the plate 24 to yieldingly urge the same to an angular position with 95 respect to the disk 16 and maintain the terminals of the plate in frictional contact with the faces of the adjacent disk. The side faces of the disk 16 are recessed at the relatively opposite ends of the slot 22 therein, as indicated at 28.

100 The inner face of the end wall 6 is recessed, as at 29, and one end of a circuit closing plate 30 is fixed to this recessed face of the plate by means of the bolt indicated at 31, to which the ground wire 32 is connected. It will be understood, of course, that the circuit closing plate 30 is suitably insulated from the wall 6, or this wall itself, as well as the other end wall 7, 110 may be of insulating material.

To the inner face of the disk 10 which is

2
rotatably mounted in the opening of the plate 7, spaced, resilient, circuit closing plates 33 are fixed at one of their ends, the free ends of said plates being normally spaced from the disk and offset, as at 34, for bearing engagement against the opposed face of the disk 14. To the fixed ends of these circuit closing plates, the wires 35 and 36 leading from the batteries and generator respectively, are connected. The disk 10 is provided upon its periphery with an outwardly projecting finger piece 36 movable in a slot provided in the top wall of the casing 5, whereby either one of the resilient plates 33 may be engaged with the contact pin fixed in the disk 14. The side wall of the casing is likewise provided with a suitable opening through which the operating heads 13, 20 and 21 project.

20 Each of the disks 14, 16 and 19 is provided with teeth 37 on its periphery which may be appropriately numbered or otherwise designated, one of the teeth being of relatively great width, as indicated at 37'.
25 When the latter teeth on the disks are in alinement with each other, the contact pins in the disks 14 and 19 are disposed in diametrically opposite relation, while the ends of the circuit closing plate 24 on the disk 16 is engaged at its ends with the first named disk at a point in spaced relation to the contact pins. The operator may now set the combination by turning the disks 16 and 19 upon their respective axes to dispose the circuit closing plate 24 in any desired relation to the contact pins in the other disk.

30 To one of the arms 9, a plurality of curved fingers 38 are fixed at one of their ends, the free ends of said fingers being provided with lugs 39. These fingers are of resilient sheet metal and the lugs 39 co-acting with the teeth on the respective disks hold said disks against casual rotation. The lugs 39 also project upwardly through a slot or opening 40 in the top wall of the casing 5. This opening in the lug may be covered by means of a hinged plate or door 41. The operator in adjusting the disks relative to each other, makes note of the combination numbers 35 which must be alined with each other in order to engage the terminals of the spring-pressed plate 23 on the central disk with the contact pins of the other disks 14 and 19. The several disks are sufficiently tight upon 45 their respective tubular shafts or spindles that when said shafts are rotated by a turning movement of the heads 13, 20 or 21, the disks will also be rotated.

From the foregoing description, taken in connection with the accompanying drawing, the construction and manner of operation of the device will be clearly and fully understood. When the intermediate disk 16 has been rotated to the proper position with respect to the other disks to engage the ends

of the plate 24 with the contacts of the latter disks, and the contact carried by the disk 19 is engaged with the resilient closure plate 30 on the end wall 6, a circuit may be closed through the switch by rotating the disk 10 to the proper position for either the batteries or the generator. When the operator desires to leave the machine, he rotates the several heads 13, 20 and 21, thereby destroying the combination, and it will be manifest that the circuits cannot be again closed through the switch by one having no knowledge of the key to the combination. The device as a whole is relatively simple in its construction and the combination required to render the switch operative may be easily and quickly changed at any time. The device may also be produced at small manufacturing cost and is highly serviceable and convenient when employed in connection with motor vehicles.

While I have herein shown and described the preferred construction and arrangement of the several elements, it is to be understood that the device is susceptible of considerable modification and I, therefore, reserve the privilege of adopting all such legitimate changes as may be fairly embodied within the spirit and scope of the invention as claimed.

Having thus fully described my invention, what I desire to claim and secure by Letters Patent is:

1. A switch of the character described including a series of relatively rotatable disks of insulating material, one of said disks being slotted, a circuit closing plate pivotally mounted centrally in the slot, a contact pin fixed in each of the adjacent disks, a spring co-acting with said plate to urge the extremities thereof into frictional engagement with the respective last named disks, a relatively stationary circuit closing plate adapted to be engaged by the contact in one of the latter disks, a ground wire connected to said plate, a circuit closing plate to engage the contact in the other of the latter disks, and means for relatively rotating the disks to predetermined positions to close the circuit.

2. A switch of the character described including a series of relatively rotatable disks of insulating material, one of said disks being slotted, a circuit closing plate pivotally mounted centrally in the slot, a contact pin fixed in each of the adjacent disks, a spring co-acting with said plate to urge the extremities thereof into frictional engagement with the respective last named disks, a relatively stationary circuit closing plate adapted to be engaged by the contact in one of the latter disks, a ground wire connected to said plate, an independently rotatable disk, spaced circuit closing members carried by said disk, either of which may be engaged

- with the contact on the other of the second named disks by the rotation of the latter disk to a predetermined position, and means for rotating the first and second named disks 5 to predetermined positions to close the circuit.
3. A switch of the character described including a series of relatively rotatable disks of insulating material, one of said disks being slotted, a circuit closing plate pivotally mounted centrally in the slot, a contact pin fixed in each of the adjacent disks, a spring co-acting with said plate to urge the extremities thereof into frictional engagement with the respective last named disks, a relatively stationary circuit closing plate adapted to be engaged by the contact in one of 10 the latter disks, a ground wire connected to said plate, an independently rotatable disk, spaced circuit closing members carried by said disk, either of which may be engaged with the contact on the other of the second 15 named disks by the rotation of the latter disk to a predetermined position, means for rotating the first and second named disks with the respective last named disks, a relatively stationary circuit closing plate adapted to be engaged by the contact in one of the latter disks, a ground wire connected to said plate, an independently rotatable disk, 20 spaced circuit closing members carried by said disk, either of which may be engaged with the contact on the other of the second named disks by the rotation of the latter disk to a predetermined position, means for 25 rotating the first and second named disks to predetermined positions to close the circuit, and means co-acting with the periphery of each of the latter disks to hold the same against casual rotation.
- 30 4. A switch of the character described including a series of relatively rotatable disks of insulating material, one of said disks being slotted, a circuit closing plate pivotally mounted centrally in the slot, a contact pin fixed in each of the adjacent disks, a spring co-acting with said plate to urge the extremities thereof into frictional engagement with the respective last named disks, a relatively stationary circuit closing plate adapted to be engaged by the contact in one of 35 the latter disks, a ground wire connected to said plate, an independently rotatable disk, spaced circuit closing members carried by said disk, either of which may be engaged with the contact on the other of the second 40 named disks by the rotation of the latter disk to a predetermined position, means for rotating the first and second named disks to predetermined positions to close the circuit, each of the latter disks being provided with 45 peripheral teeth having indicative characters thereon, and resilient fingers provided with terminal lugs to co-act with the teeth of the respective disks and hold the same against 50 casual rotation.
- 55
- In testimony whereof I hereunto affix my signature in the presence of two witnesses.
